(57) **CLAIM**

The ornamental design for a dachshund dog-shaped child's trolley toy, as shown and described.

DESCRIPTION

FIG. 1 is a front lateral view of the design.

FIG. 2 is a rear lateral view of the design.

FIG. 3 is a side view of the design; and,

FIG. 4 is a front side perspective view thereof.

The broken line showing is for illustrative purposes only, and forms no part of the claimed design.

The design disclosed and claimed herein, and illustrated in the above-described figures, is not intended to include the leash depicted in said figures.
